SUPPORT FOR CLOTHES HANGER

Maude Landin, 436 Convent Ave.,
New York, N.Y. 10031

Filed Aug. 11, 1972, Ser. No. 279,929

Term of patent 14 years

Int. Cl. D6—08

U.S. Cl. D6—85

FIG. 1 is a perspective view of the support for clothes hangers;

FIG. 2 is a front elevational view thereof;

FIG. 3 is a bottom plan view thereof; and

FIG. 4 is an end view thereof, the view from the other end being identical.

I claim:

The ornamental design for support for clothes hanger, as shown.
